N. C. KOSTENBAUDER

LATCH FOR MINE CAR DOORS

Filed Aug. 18, 1924

Patented July 28, 1925.

1,547,878

UNITED STATES PATENT OFFICE.

NELSON C. KOSTENBAUDER, OF ARISTES, PENNSYLVANIA.

LATCH FOR MINE-CAR DOORS.

Application filed August 18, 1924. Serial No. 732,725.

To all whom it may concern:

Be it known that I, NELSON C. KOSTENBAUDER, a citizen of the United States, residing at Aristes, in the county of Columbia and State of Pennsylvania, have invented certain new and useful Improvements in a Latch for Mine-Car Doors, of which the following is a specification.

This invention relates to improvements in latches for mine car doors and has for its principal object to provide a simple and efficient means for holding the swinging door of a mine car in a closed position against accidental opening and thereby preventing the loss of coal from the car while the latter is in transit.

Another important object of the invention is to provide a latch for car doors wherein the same may be readily and easily actuated for moving the door engaging member out of engagement with the door to permit the swinging movement thereof after the mine car has reached its destination and the contents of the car are to be discharged therefrom.

A further object of the invention is to provide a latch for mine car doors of the above mentioned character, which is of such a construction as to obviate the necessity of employing any complicated tool or necessitating the loss of considerable time and labor in releasing the latch from its locked position.

A still further object of the invention is to provide a latch for mine car doors of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is an elevational view of a mine car door showing the manner in which my improved invention is associated therewith.

Figure 2 is a top plan view thereof, and

Figure 3 is a side elevation of the same.

In the drawing wherein for the purpose of illustration is shown the preferred embodiment of my invention, the numeral 1 designates a portion of a mine car, the door thereof being illustrated at 2. The door is

supported at its upper edge on the transversely extending shaft 3 which is journaled in the brackets 4 mounted on the top of the sides of the car body or standards and whereby the door is adapted for upward swinging movement in the manner well known in the art.

The latches now universally in use on the doors of mine cars frequently become disengaged due to the vibration of the car while in transit which results in the loss of a considerable amount of coal and frequently causes trouble by reason of the fact that the coal will cover the tracks over which the cars travel. Furthermore, with the latches now in use, it is necessary to use a bar or some other heavy object when desirous of releasing the latch in order to open the door or gate 5. This obviously necessitates the loss of considerable length of time and labor. In order to overcome the above disadvantages, I have provided a latch which is very simple in construction, as well as easily operated.

My improved latch comprises an elongated rod 5 which is rotatably supported in suitable bearings 6 mounted on the bottom of the car body adjacent the outer lower edge of the door 2 in the manner clearly illustrated in the drawing. The rod 5 is bent intermediate its ends to provide a pair of upstanding arms 7 and 8 respectively, the same being adapted for engagement with the outer face of the door in the manner as also clearly illustrated in the drawing. The arms 7 and 8 provide a means for preventing the outward swinging movement of the door 2 when in engagement therewith and may further be swung out of engagement with the door to permit the latter in the manner hereinafter to be more fully described.

One end of the rod 5 terminates in an upward extension 9 the same being disposed adjacent one of the standards 10 to the sides of the car body adjacent the lower end of the same and the door 2. The extension 9 provides what I term as a bolt and cooperating therewith is the keeper or retaining loop 11.

The retaining loop 11 is formed on the outer end of the rod 12 which extends through a suitable opening provided in the standard 10 adjacent the extension or bolt 9 formed on one end of the rod 5 and is adapted to rotate therein. This rod 12 ex-

tends longitudinally in respect to the car and laterally with respect to the door locking means 5. Reinforcing plates such as are shown at 13 are secured on the opposite sides 5 of the standard through which the rod 12 extends and the plates are provided with openings adapted for registry with the opening in the standard for receiving the rod 12. The rod 12 terminates at its opposite 10 end in the downwardly extending portion 14 which forms an actuating lever in the manner in which the same will be presently described.

When the parts are normally in the position as shown in the drawing, wherein the arms 7 and 8 of the rod 5 engage the outer face of the door 2 and the retaining loop or keeper 11 disposed over the upper end of the extension or bolt 9, the door 2 is held 20 in a locked position against outward swinging movement in such a manner as to prevent any possibility of the latch becoming unfastened while the mine car is in transit. After the mine car has reached its destination 25 and the contents thereof are to be discharged it is only necessary to swing upward on the lever 14 in the manner as illustrated in the dotted lines in Figure 1 of the drawing whereby the retaining loop or keeper 11 is moved out of engagement with the upper end of the bolt 9 and the rod 5 may then be free to rotate in the bearing 6 due to the weight of the lading against the door, causing the arms 7 and 8 to swing 35 outwardly out of engagement with the door 2 and permit the latter to swing outwardly and upwardly and thereby permit the coal to be emptied from the car.

When it is desired to hold the door in its 40 closed position against outward swinging movement, it will only be necessary to move the arms 7 and 8 upwardly into engagement with the outer face of the door by raising the extension 9 and by swinging the lever 14 downwardly, the keeper or retaining loop 11 will again be disposed over the upper end of the bolt 9.

It will thus be seen from the foregoing 50 description, that a latch for mine car doors has been provided which will at all times be positive and efficient in carrying out the purposes for which the same is designated and will not in any way interfere with the operation of the mine car when in transit.

55 While I have shown the preferred embodiment

of my invention it is to be understood that various changes in the size, shape and arrangement of parts may be resorted to without departing from the spirit of the invention and the scope of the appended 60 claims.

Having thus described the invention, what I claim is: —

1. In combination with an upwardly swinging door for mine cars, of a latch therefor comprising an elongated rod rotatably supported on the bottom of the car adjacent the outer lower portion of the door, door engaging members associated with the rod for preventing the outward swinging movement of the same, means for locking the rod against rotation for holding the door engaging members in an operative position, said means comprising an angular extension on one end of the rod providing a bolt, a keeper supported on the side car adjacent the door for engagement with the bolt, said keeper comprising a rod on the side of the car adapted for rotation thereon, one end thereof being provided with a retaining loop for engagement with the end of the extension, and a lever on the opposite end of the rod for moving the retaining loop into and out of engagement with the bolt.

2. In combination with the upwardly swinging door of a mine car, of a latch therefor comprising an elongated rod rotatably supported on the bottom of the body of the car adjacent the outer lower portion of the door, said rod being bent intermediate its ends to provide a pair of upwardly extending arms adapted for engagement with the outer face of the door to prevent the outward swinging movement thereof, means for locking the rod against rotation and holding the arms in locked engagement with the door, said means comprising an upward extension formed on one end of the rod, providing a bolt, a keeper adapted for cooperation with the bolt, said keeper comprising a rod rotatably supported on the side of the car, one end of the rod having a retaining loop formed thereon for receiving the upper end of the bolt when in one position, and a lever formed on the other end of the rod for actuating the same to move the loop out of engagement or into engagement with the bolt.

In testimony whereof I affix my signature.

NELSON C. KOSTENBAUDER.
